UNITED STATES PATENT OFFICE.

JAY HUNGERFORD SMITH, OF ROCHESTER, NEW YORK.

STICKY FLY-PAPER.

SPECIFICATION forming part of Letters Patent No. 469,021, dated February 16, 1892.

(Application filed May 28, 1891. Serial No. 394,434. No specimens.)

To all whom it may concern:

Be it known that I, JAY HUNGERFORD SMITH, of Rochester, in the county of Monroe and State of New York, have invented a certain new and 5 useful Improvement in Fly-Paper, of which the following is a specification.

My improvement relates to fly-paper made in double sheets, one side of which is provided with sticky material and the other forms a 10 flap or cover which turns down over it.

The invention consists in the peculiar folding of the edge of the paper, forming a double V, the lower fold forming an inclosure which prevents the adhesive material from running 15 off, and the upper fold forming a cushion or pad that prevents contact of the two sheets at the edges, and also a finger-hold by which the paper can be easily opened.

In the accompanying drawings, Figure 1 is 20 a perspective view of a sheet of fly-paper provided with my improvement partially folded and with one corner torn away to show the folding of the edges. Fig. 2 is a plan view of the same laid open. Fig. 3 is a cross-section 25 in the folded position.

A A' indicate the two halves of the sheet, which is folded in the center one half over the other to inclose the sticky surface. The edge of one half of the sheet is folded, as shown at 30 a a'. The edge is first folded over inward of double width and then folded back on itself, the free margin standing outward. This makes a double-V fold inclosing angular

spaces, the lower one standing inward and the upper one outward, as shown.

By the construction above described the device is all made from one sheet of paper; the lower groove of the edge folding serving to prevent the escape of the adhesive material, while the upper loose flap serves as a cushion 40 or pad to receive the upper sheet and prevent it from coming in contact with the lower one. These double folds make such a thickness at the edge that even with the use of very thin paper the leaves are kept separated at the 45 edges. The loose flap also serves as a convenient finger-hold in opening the sheets.

Having described my invention, I do not claim a single fold; nor do I claim strips placed between the sheets to separate the 50 same.

What I claim as new, and desire to secure by Letters Patent, is—

A sheet of fly-paper with folds of double-V form at its edge, the lower fold serving as 55 a stop to the escape of the adhesive material and the upper fold forming a free flap that serves as a cushion and a finger-hold, as and for the purpose specified.

In witness whereof I have hereunto signed 60 my name in the presence of two subscribing witnesses.

JAY HUNGERFORD SMITH.
